Primary Examiner—Gary D. Watson(74) *Attorney, Agent, or Firm*—MacCord Mason PLLC(57) **CLAIM**

The ornamental design for a chair, as shown and described.

DESCRIPTION

FIG. 1 is a perspective view of a chair showing my new design;

FIG. 2 is a front view thereof;

FIG. 3 is a side view, the opposite side being a mirror image thereof;

FIG. 4 is a back view thereof;

FIG. 5 is a top view; and,

FIG. 6 is a second embodiment of the design shown in FIGS. 1–5.

The bottom elevation view of the design is not shown and would not depict any aspect of the invention not already shown in the figures.
